(57) CLAIM

I claim the ornamental design for a toothbrush holder, as shown and described.

DESCRIPTION

FIG. 1 is a perspective view of the toothbrush holder showing my new design;

FIG. 2 is a front elevational view thereof, the rear elevation being a mirror image of that shown;

FIG. 3 is a right side elevational view thereof, the left side elevation being a mirror image of that shown;

FIG. 4 is a top plan view thereof; and,

FIG. 5 is a bottom plan view thereof.

The broken-line disclosure of a toothbrush holder shown in FIG. 1 is for illustrative purposes only and forms no part of the claimed design.
